CLAIM

The ornamental design for a device for electronic monitoring system, as shown and described.

DESCRIPTION

FIG. 1 is a perspective view of a device for electronic monitoring system according to the present invention.

FIG. 2 is a front view of the device for electronic monitoring system of FIG. 1.

FIG. 3 is a rear view of the device for electronic monitoring system of FIG. 1.

FIG. 4 is a left side view of the device for electronic monitoring system of FIG. 1.

FIG. 5 is a right side view of the device for electronic monitoring system of FIG. 1.

FIG. 6 is a top view of the device for electronic monitoring system of FIG. 1; and,

FIG. 7 is a bottom view of the device for electronic monitoring system of FIG. 1.

The device is for tracking the location of a monitored person, and the device may be worn on the person's body such as the ankle.
